Attns.

UNITED STATES PATENT OFFICE

THEODOR RICHTER, OF SPANDAU, GERMANY

FRAME FOR COMBINED MOWING AND BINDING MACHINES

Application filed July 20, 1925, Serial No. 44,923, and in Germany November 7, 1924.

This invention relates to a further improvement in the frame which forms the subject of my Patent No. 1,567,299, granted Dec. 29, 1925 and which consists of four single-piece main members pressed from sheet metal and with the main shaft journaled in bearing shells also integrally pressed out of the material. The characteristic feature of the present invention lies in the fact that the main members lying transverse to the working direction of the machine are prolonged beyond the members lying in the working direction of the machine and enclosing the driving wheel, and are there provided with pressed out bearing shells for the crank and chain wheel shaft, while the member carried by the land wheel is also pressed from sheet metal and with its rear end engages in a bend of the appurtenant main member. The novel construction simplifies the frame and improves the journalling of the driving gear units, thereby providing the foundation of a machine of this kind which is at the same time cheaper and more reliable in use than any hitherto produced.

The accompanying drawing shows an example of the invention; the figures show two perspective views whereof:

Figure 1 shows the frame stripped and Fig. 2 shows the frame with the most important driving gear units assembled thereon.

In the drawings, a and a^1 indicate the two single-piece pressed main members lying transverse to the direction in which the machine travels when working, whereof a^1 serves for the attachment of the knife beam a^2 . b and c indicate the other pair of single-piece pressed members lying in the working direction, whereof member c terminates in the integral draw-eye f , h indicates the main shaft which is journaled in the pressed-out bearing shells e of the pair of members b , c . The latter also serve for journalling the driving wheel j , which by means of sprocket wheel j^1 and a chain (not shown) can be raised or lowered in a hoop-shaped guide k according to whether the machine is to be carried by the wheel j for operation in the field, or for journeying to or from the field, in

which latter case it rests upon special wheels (not part of this invention and not shown on the drawing) and moves in a longitudinal direction.

According to the invention the members a and a^1 are prolonged outwardly beyond the member b and at these parts are formed with pressed bearings m , which serve to take the shaft n . This is provided at one end with a crank o for operating the cutting knife, and at the other end with a chain wheel p which drives all the remaining movable parts of the machine, such as the conveyor band, the winder, the knotter, and so on. The transmission of power between the main shaft h driven from the main wheel j by chain and chain wheel r and the shaft n , is effected by means of a bevel wheel pair s .

The frame is still further improved in that the frame portion u carrying the land wheel t is produced from a pressed sheet member. This engages with its reduced rear end in a bend of the member a , while its forward end lies upon the knife beam carrier a^1 and ensures rigidity and therewith faultless operation of the cutting off device.

The arrangement of the pressed member u does not pre-suppose the existence of the bearing portions m integral with the members a , a^1 , or vice versa.

I claim:

1. A frame for a mowing and binding machine consisting of two longitudinal members, two members located transversely thereof and rigidly connected thereto, lugs projecting beyond the longitudinal members and integral with corresponding ends on one side of both transverse members projecting beyond the longitudinal members for carrying the crank and chain shaft a cranked portion to one of said transverse members and a member connecting the ends of said transverse members for carrying a land wheel.

2. A frame for a mowing and binding machine comprising, in combination, two longitudinal members disposed in the direction of travel of the machine, a driving wheel journaled in bearings in said longitudinal members, transverse members connecting the ends of said longitudinal members, lugs project-

ing beyond the longitudinal members and integral with corresponding ends of both transverse members said lugs projecting beyond a longitudinal member, a crank and chain shaft carried by said lugs, a cranked portion to one of said transverse members and a third longitudinal member connecting the ends of said transverse members and adapted to carry a land wheel.
